US00D566971S

(12) United States Design Patent (10) Patent No.: US D566,971 S
 Harkenrider (45) Date of Patent: * Apr. 22, 2008

- (54) NON-WOVEN TEXTILE
 (75) Inventor: Gregory P. Harkenrider, Thornton,
 CO (US)
 (73) Assignee: Hunter Douglas Inc., Upper Saddle
 River, NJ (US)
 () Term: 14 Years
 (21) Appl. No.: 29/287,660
 (22) Filed: Sep. 5, 2007

Related U.S. Application Data

- (60) Continuation of application No. 29/269,837, filed on Dec. 11, 2006, now Pat. No. Des. 554,868, which is a continuation of application No. 29/263,989, filed on Aug. 2, 2006, now Pat. No. Des. 536,878, which is a continuation of application No. 29/255,359, filed on Mar. 8, 2006, now Pat. No. Des. 529,297, which is a division of application No. 29/226,187, filed on Mar. 25, 2005, now Pat. No. Des. 522,253.
